UNITED STATES PATENT OFFICE.

GUSTAF JOHNSON, OF CHICAGO, ILLINOIS.

WEATHER-STRIP.

1,096,540.

Specification of Letters Patent.

Patented May 12, 1914.

Application filed February 17, 1912, Serial No. 678,278. Renewed November 3, 1913. Serial No. 799,024.

To all whom it may concern:

Be it known that I, GUSTAF JOHNSON, a citizen of the United States, and a resident of the city of Chicago, county of Cook, and State of Illinois, have invented certain new and useful Improvements in Weather-Strips, of which the following is a specification.

My invention relates to improvements in weather strips, and has for its object the production of a construction which will be durable and economical and of high efficiency in use.

Other objects will appear hereinafter.

With these objects in view, my invention consists in the combinations and arrangements of parts hereinafter described and claimed.

My invention will be best understood by reference to the accompanying drawing forming a part of this specification, and in which—

Figure 1 is a sectional front elevation of a window sash frame equipped with weather strips embodying my invention; Fig. 2 is a vertical section through the sash frame, the lower sash being shown in elevation, the upper sash being removed, Figs. 3 and 4 are enlarged detail fragmentary sections taken on substantially lines *x-x* and *y-y*, respectively, of Fig. 1, and Fig. 5 is an enlarged detail elevation of one of the parts of the weather strip, detached.

The preferred form of construction, as illustrated in the drawing, comprises a window sash frame 1 in the opposite sides of which are provided the usual inner and outer or lower and upper sash grooves 2 and 3, respectively. Arranged in the frame 1, with their lateral edges slidably engaging the grooves 2 and 3, are the inner and outer or lower and upper sashes 4 and 5, respectively.

Arranged in the bottom of each of the grooves 2 and 3 is a strip 6 formed preferably of sheet metal, which is secured in position by screws 7. Formed in the strip 6 adjacent one of the longitudinal edges thereof, is an outwardly projecting T-shaped tongue 8. The tongue 8 is embraced by or inter-lockingly engaged with a channel strip 9 which is mounted in a longitudinally extending groove 10 formed in the lateral edges of the sashes 4 and 5, as clearly shown in Fig. 3, the strips 9 being secured in position by screws 11 which pass therethrough at intervals.

Each of the strips 9 is formed at its outer edges with inwardly projecting flanges 12 which are adapted to engage behind the laterally projecting head portions of the corresponding tongue 8, the inner edges thereof being adapted to forcibly engage against the opposite sides of the web or leg of said tongue, as clearly shown. The head of each of the tongues 8 is of a width corresponding with the inside width of the corresponding strip 9, so that the longitudinal edges of said head engage against the inner surfaces of the opposite sides of the channel. With this arrangement it will be seen that a double joint is effected between corresponding strips 6 and 9, which results in the effectual exclusion of the weather. The engagement of the flanges 12 behind the laterally projecting portions of the corresponding tongue 8, obviates all possibility of disengagement of coöperating parts of the weather strip where the window sash is very loose in the frame or upon excessive shrinking of the sash in the frame. The strips 6 in the respective grooves 2 and 3, are positioned for engagement with the strips 9 carried by the corresponding sashes when the latter are in normal position, hence said strips 6 do not extend the entire length of said grooves, this being unnecessary.

Arranged between the contiguous surfaces of the overlapping transverse bars of the sashes 4 and 5 (when the latter are in normal position) and the lower transverse bar of the sash 4 and the adjacent side of the sill of frame 1, is an elongated metallic strip 13. The edge 14 of each of said strips 13 is bent inwardly into engagement with a groove 15 formed in one of the contiguous surfaces between which the same is arranged, the extreme edge 16 of the portion 14 being turned back in order to automatically engage one side of the groove 15, when the portion 14 is inserted therein, to securely fasten the latter in position. The opposite edge of each of the strips 13 is free and is normally inclined outwardly so as to be adapted to forcibly engage against the adjacent contiguous surface, as clearly shown in Fig. 4. The extreme edge 17 of said free edge portion is bent at right angles to the body thereof for loosely engaging a groove 18 which is formed in the same surface as bears the groove 15. One 110 of the strips 13 is preferably carried by the lower bar of the upper or outer sash, the

lower edge portion of the strip being free for obvious reasons. The other of the strips 13 is secured to the lower bar of the sash 4, the lower edge portion of said strip being secured and the upper edge portion free for engaging against the adjacent side of the window sill, as will be readily understood. Thus provision is made for effectually excluding the weather from the transverse joints in the window construction. By the use of both of the strips described, that is of those coöperating with the lateral edges of the sashes and those coöperating with the transverse edges thereof, the exclusion of the weather will be positive and effectual.

While I have illustrated and described the preferred form of construction for carrying my invention into effect, this is capable of variation and modification without departing from the spirit of the invention. I, therefore, do not wish to be limited to the exact details of construction set forth, but desire to avail myself of such variations and modifications as come within the scope of the appended claim.

Having described my invention, what I

claim as new and desire to secure by Letters Patent, is:

The combination with a window-frame, and a sash in said frame provided with longitudinal grooves in its vertical edges a member substantially C-shaped in cross section secured in each of said grooves and snugly fitting therein, the said C-shaped member having inturned edges and being arranged entirely within the groove, and coacting members on the adjacent portion of the frame, said coacting members being substantially T-shaped and comprising a securing base, a web portion consisting of spaced resilient members fitting snugly against the parallel edges of the C-shaped member and a head portion fitting snugly against the opposite sides of said C-shaped member, substantially as described.

In testimony whereof I have signed my name to this specification in the presence of two subscribing witnesses.

GUSTAF JOHNSON.
